DESIGN FOR A SAND GLASS

Sidney Lazarus, Brooklyn, N. Y., assignor to Seed Filter & Mfg. Co. Inc., New York, N. Y., a corporation of New York

Application November 12, 1940, Serial No. 96,460

Term of patent 7 years

To all whom it may concern:

Be it known that I, Sidney Lazarus, a citizen of the United States, residing at Brooklyn, county of Kings, State of New York, have invented a new, original, and ornamental Design for a Sand Glass, of which the following is a specification, reference being had to the accompanying drawing, forming part thereof.

Fig. 1 is a side view of a sand glass showing
my new design.

Fig. 2 is a sectional view taken on the plane of the line 2—2 of Fig. 1.

I claim:

The ornamental design for a sand glass, as shown.

SIDNEY LAZARUS.
